STRAW DISPENSER

Robert K. Tiedeman, Packanack Lake, N. J.

Application February 15, 1949, Serial No. 76,516

9 Claims. (Cl. 312—78)

1

This invention relates to dispensers and is concerned particularly with improvements in sanitary dispensers for drinking straws, being adapted for use in soda fountains and the like.

While straw dispensers are known in the art, none of them are known to meet strict health, cleanliness and sanitary requirements for devices used in handling of foodstuffs and the like, even though they may be adequate from the standpoint of serviceability and operativeness. Accordingly, it is an object of this invention to provide a straw dispenser which is wholly closed and which may be loaded from packages of straws without an operator touching either the straws or the interior of the dispenser, thereby avoiding the possibility of transmission of disease. It is a further object to provide a dispenser which may be disassembled and cleaned without difficulty so that the dispenser may meet sanitary requirements which may be or are established by governmental agencies. Another object of the invention is to provide a straw dispenser which is positive and simple in operation so that no indoctrination on the part of the user or the storekeeper is necessary. Another object of the invention is to provide a dispenser mechanism which is positive in operation and which is substantially trouble-free from the viewpoint of disruption of the mechanism due to defective straws, and which is so simple as to be most unlikely to jam or fail in operation. Another object of the invention is to provide a straw dispenser which is easily producible by production methods, so that the cost of the device will be minimized.

Still another object of the invention is to provide, for cooperation with the dispenser of the invention, a special package adapted for loading the dispenser; in such a manner that the contents of the package may be loaded into a dispenser without touching the package contents.

Further objects of the invention will become clear in viewing the drawings in connection with the detailed description following. The drawings and description are to be taken only as illustrative of one mode of practicing the invention and are not to be construed as limiting the scope thereof. The definition of the limits of the invention are set forth only in the appended claims.

In the drawings in which similar reference characters represent similar parts,

Fig. 1 is a perspective view of a straw dispenser of the invention, showing portions thereof in phantom and portions thereof in solid lines;

Fig. 2 is a longitudinal section through a straw

2

package appropriate for use with the invention;

Fig. 3 is a plan of the straw package; and

Fig. 4 is a side elevation, partly broken away and partly in section, showing the straw dispenser and the application of a straw package thereto for filling the dispenser.

The dispenser consists of a substantially rectangular hollow container 10 fabricated from metal, or plastic, as desired, the container being closed at its top, as at 12. An offset portion 14 is provided in the container for a purpose which will become apparent. The bottom of the container is open, for straw loading purposes, the opening being closable by a removable closure 16 (Fig. 4). Within the back of the container and hinged to the sides thereof are spaced feed flaps 18 which preferably comprise a wire frame 20 covered by a plate 22, the feed flaps being hinged on rods 24 which, at their ends, engage the sides 20 of the container. The flap hinges include springs 26 which normally urge the flaps leftwardly as shown to move contained straws toward the opposite side of the dispenser for feeding, as will be described. The flaps 18 are movable between a vertical position and a nearly horizontal position as shown in the upper portion of Fig. 4 so that as straws are dispensed, those within the container will be moved leftwardly as shown for ultimate ejection by the ejector and traversing mechanism best shown in Fig. 1.

The ejection and traversing mechanism is wholly carried by an edge-flanged plate 28 which is assembled in the container 10, the latter having formed therein a suitable track to receive the plate 28. After assembly of the plate the latter is held in position by the bottom closure 16 which engages suitable ledges 30 formed in the container. The straws engaged by the flaps 18 are pressed against the plate 28. A lower corner of the plate is cut away as at 31 and an ejector 32 is mounted for vertical reciprocation at this cutout, the ejector carrying a shelf 34 engageable with the bottom of a straw and the ejector further being constrained to vertical sliding by clips 36 on the back of the plate 28. These clips may either be spot welded to the plate 28 or may be formed by punched upsets from the plate itself.

An operating rod 38 is mounted for vertical reciprocation on the back of the plate 28, being secured for sliding by clips 40 punched out of the plate proper and folded around the rod. This rod extends through an opening in the top 12 of the container 10 and carries an appropriate and decorative handle 42. The ejector 32

and rod are connected to one another through a rocker 44 centrally pivoted to the plate 28 by a stud 46, the ends of the rocker 44 being provided with slots 48 and 50 engaging pins 52 and 54 which are respectively fixed to the rod 38 and the ejector 32. Thus, when the knob 42 is pressed downwardly, the ejector 32 is caused to rise and conversely, when the knob 42 rises, the ejector 32 drops to the bottom of the container. When a straw is disposed with its bottom on the ejector shelf 34 and when the knob 42 is pressed, the straw is moved upwardly and passes through an opening 56 formed in the top 12 of the container 10. The hole 56 is normally closed by a small trapdoor 58 hinged to the container and raised when a straw is ejected through the hole. Upon removal of the partially ejected straw from the container, the trapdoor 58 drops closed to prevent the entry of foreign matter into the container whereby the straws are kept clean.

The plate 28 is provided with two similar lateral apertures 60 through each of which a traversing mechanism may at times protrude. Since both of the traversing mechanisms are the same, a description of one will suffice and the same reference characters are applied to both. Across the aperture 60 and engaged in the end flanges 62 of the plate 28 is a pin or rod 64 upon which is slidably and turnably mounted a feed comb 66 preferably fabricated from sheet metal and having a portion 67 wrapped around the pin 64. A protruding portion of the comb 66 is scalloped to provide a plurality of substantially semi-circular notches 68, the size and shape of these notches being such as to readily receive straws pressed against the plate 28 by the flaps 18. These combs 66 serve, by their partial rotation and longitudinal movement, to feed straws resting against the plate 28 laterally along the plate toward the ejector 32 so that upon each operation of the operating knob 42, a straw will be ejected and a new straw will be placed in loading position for subsequent ejection by another operation of the rod 38 and its knob 42.

The plate 28 is provided with a stop portion 70 upon which the comb 66 may rest, this stop establishing a lowermost position to which the comb 66 can turn and in which position, the notches 68 protrude outwardly from the plate 28 to engage straws. From the back portion of each comb 66, a tab 72 projects, which is engaged by a spring 74, the upper end of the spring being engaged with a tab 76 upset from the plate 28. The tabs 72 and 76 are so related that the spring 74 continuously urges the comb 66 rightwardly as shown and also, in a clockwise direction as shown, for engagement with the straws and for movement of the straws from left to right.

The comb 66 is provided with a tab 78, on one side of the rod 38, which is engaged by a depressor portion 80 of a cam element 82 secured to the rod 38. The tab 78 is substantially coplanar with the comb 66 so that it lies horizontally when the comb teeth project into the container for straw engagement. The comb 66 is also provided with a tab 84 which, when the comb 66 is horizontal, has an upstanding projection 86. This tab is engaged by a cam face 88 of the rod cam 82.

When the rod 38 is pressed downwardly, the depressor 80 engages the tab 78 and tilts the comb 66 upwardly out of engagement with the

straws. Concurrently, the rocker 44 is swung to raise the ejector 32 and to eject a straw from the container through the port 56. As the rod 38 moves downwardly, the cam face 88 engages the tab 84, shifting the comb 66 laterally (leftwardly as shown) against the tension of the spring 74. This traversing continues until the rod 38 reaches the bottom of its stroke at which time the tab 78 of the comb 66 has moved leftwardly and disengages the depressor 80 whereupon the comb rotates under the influence of the spring 74 and the comb teeth protrude from the plate 28 and engage the straws lying against the plate. Now, the rod 38 is released and is restored to a vertical position by a spring 90 engaged at one end with the lower cam 82 and at its upper end with a tab 92 upset from the back plate 28. As the rod 38 rises, with the comb 66 in the horizontal position, the cam face 88 leaves the tab 84 and the comb is prevented from moving to the right due to the depressor 80 engaging one side of the tab 78, the comb 66 being urged toward the right by the spring 74. When the rod 38 reaches its uppermost position, the depressor 80 rises above the tab 78, thereby freeing the comb 66 for movement to the right under the influence of the spring 74. Upon such movement, the straws within the container, engaged by the teeth of the comb 66, are moved to the right, the most extreme straw on the right hand side thereby being placed in position over the shelf 34 on the ejector 32, in readiness for ejection when the rod 38 is next depressed.

By the action of the tabs 18, a plurality of straws will at all times be held against the back plate 28 for engagement by the teeth of the comb 66, until the supply of straws within the container may be exhausted. As the straw container becomes nearly empty, there may be an insufficient number of straws against the back plate 28 to fill all of the notches in the two combs 66 so that in this condition, ejection of straws may not occur necessarily with every stroke of the rod 38. However, if delivery of a straw should fail, repeated operation of the rod 38 will finally deliver the last straw in the container without fail.

If one or more straws, lying against the plate 28, should become tilted, this will not interfere with the successful operation of the dispenser. The teeth of the two combs by repeated operation of the operating rod 38 will eventually move the straw to an erect position over the ejector shelf 34 for ultimate delivery.

It will be noted that the container is constructed with the offset portion 14 at one corner which is internally formed as a channel to receive a straw which is in position for ejection, overlying the ejector shelf 34 and lying immediately beneath the ejection hole 56. By this channel, a straw in position for ejection is isolated from the balance of the straw supply within the container and more positive operation of the dispenser is assured.

Referring to Figs. 2, 3 and 4, a special type of straw package is shown which is particularly adapted for use with the dispenser of this invention to enable sanitary filling of the dispenser. The use of such a package is not essential however as the dispenser can if necessary be filled by hand from any conventional straw package. To assure sanitary usage of the dispenser the special package herein shown and described is recommended. This package consists of an or-

ordinary soft cardboard box 100 the bottom edges of which are folded or rolled as at 102 to comprise a bottom stop. A bottom for the package comprises a cardboard portion 104 whose edges are folded upwardly as at 106, this bottom portion lying within the package and against the folded portions 102. The straws are loaded into the package and against the bottom 104. The top of the package is closed in the conventional manner by folded tabs 108, 110 and 112, the tab 108 being provided with a slot and the tab 110 being provided with a slot engaging tongue 114 by which the box is held closed.

To fill the container 10 when the supply of straws therein has become small but not necessarily exhausted, a loading door 116, hinged at 118 to the container bottom closure 16, is opened and the top of the straw package is inserted through the thus formed opening into the container. The package, when it is pushed into the container, will raise one or both of the feed flaps 18 as shown in Fig. 4 whereupon the operator presses upon the bottom 104 of the package. The straws open up the top flaps of the package and are pushed into the container, whereupon the package itself, along with the bottom closure 104, is withdrawn from the container leaving the straws therein. Thereupon, the door 116 may be closed either manually or by a spring hinge at the point 118. The flaps 18 then press the loaded straws toward the back plate 28 and the dispenser is again ready for normal operation.

A latch 118 is shown at the bottom right hand side of the container in Fig. 4 to hold the door 116 closed, and a knob 120 on the door 116 allows of easy opening of the door for loading purposes.

The container is provided with projections 122 along with the projections 30 to locate the loading position for the straw package so that it will be properly centered when the door 116 is opened. These projections are so disposed that the package will be held clear of the back plate 28 and also, of the hinge mountings 24 for the flaps 18 so that unskilled operators will be prevented from loading the dispenser in an incorrect manner. The hinge rods 24 may be shrouded by guides 123 to assist in centering the package when the dispenser is being loaded.

As inferred heretofore, the bottom closure 16 of the container, along with the loading door 116, may comprise a single sub-assembly which is inserted into the bottom of the container 10 in a manner which is clear from the drawing in Fig. 4. The part 16 is registered in grooves associated with the container projections 30 and serves to hold the back plate 28 in the container, the door 116 being free for opening and closing after the portion 16 is in proper position. Should it be desirable to disassemble the dispenser for cleaning or any other purpose, the door 116 is opened and the portion 16 is slid rightwardly out of its container slots. Then, the knob 42 may be removed from the rod 38 and the entire ejection and loading assembly mounted upon the back plate 28 may be removed as a unit by withdrawal through the bottom of the container.

With the ejecting and loading mechanism constituting a complete sub-assembly, it can be easily cleaned and adjusted, all elements thereof being in plain view, leaving no opportunity for accretions of foreign matter which might aggregate to form a sanitation hazard.

The dispenser and its component parts are all 75 substantially horizontal axis, adjacent an interior

readily fabricated at low cost, the mechanism elements all comprising, preferably, thin rust or corrosion resistant sheets formed into their ultimate configuration by stamping operations. The 5 container proper may either be of metal or of a molded plastic composition. If desired, when the container is made of plastic, portions of it may be made transparent so that the straw contents are visible. Preferably, the portions of the container embracing the ejection and feed mechanism would be opaque but this is not essential. The dispenser may be made in any desired size to accommodate a supply of a considerable number of straws to avoid the need for frequent reloading.

Though but a single embodiment illustrating the invention has been illustrated and described, it is to be understood that the invention may be applied in various forms. Changes may be made 20 in the arrangements shown without departing from the spirit or scope of the invention as will be apparent to those skilled in the art and reference should be made to the appended claims for a definition of the limits of the invention.

What is claimed is:

1. A soda straw dispenser comprising a container within which a quantity of straws is adapted to be inserted from a package, a feed mechanism on a wall engageable and disengageable 30 with the plurality of straws adjacent said wall, an ejector adjacent said wall, said container having an opening aligned with said ejector through which a straw may be ejected, an operating member on said container movable in one direction to move said ejector to eject a straw and movable 35 in the opposite direction to restore said ejector and means connecting said member to said feed mechanism to disengage the mechanism from said straws and to traverse the mechanism away from said ejector upon actuation of the member 40 in one direction, and to engage the mechanism with the straws and to traverse the mechanism toward said ejector upon actuation of said member in the other direction.

2. A soda straw dispenser comprising a container within which a quantity of straws is adapted to be inserted from a package, follower means 45 movable within said container, adjacent an interior wall thereof contacting contained straws to urge them toward the opposite side of said container, feed mechanism on said opposite wall engageable and disengageable with the plurality of straws adjacent said opposite wall, an ejector at one end of said opposite wall, said container having an opening aligned with said ejector through which a straw may be ejected, an operating member on said container movable in one direction to move said ejector to eject a straw and movable 50 in the opposite direction to restore said ejector, and means connecting said member to said feed mechanism to disengage the mechanism from said straws and to traverse the mechanism away from said ejector upon actuation of the member in one direction, and to engage the mechanism with the straws and to traverse the mechanism toward said ejector upon actuation of said member in the other direction.

3. A soda straw dispenser comprising a container within which a quantity of straws is adapted to be inserted from a package, the straws being disposed in said container in a substantially vertical position and the container having a rectangular cross section, a spring pressed swinging feed plate hinged within said container on a substantially horizontal axis, adjacent an interior

wall thereof, having an edge contacting a portion of the contained straws to urge them toward the opposite side of said container, a lateral feed mechanism on said opposite wall engageable and disengageable with the plurality of straws adjacent said opposite wall, an ejector at one end of said opposite wall, said container having an opening alined with said ejector through which a straw may be ejected, an operating member on said container movable in one direction to raise said ejector and to eject a straw and movable in the opposite direction to lower said ejector, and means connecting said member to said feed mechanism to disengage the mechanism from said straws and to traverse the mechanism away from said ejector upon lowering of the member, and to engage the mechanism with the straws and to traverse the mechanism toward said ejector upon raising of said member.

4. A soda straw dispenser comprising a container within which a quantity of straws is adapted to be inserted from a package, the straws being disposed in said container in a substantially vertical position and the container having a rectangular cross section, a spring pressed swinging feed plate hinged within said container on a substantially horizontal axis, adjacent an interior wall thereof, having an edge contacting a portion of the contained straws to urge them toward the opposite side of said container, a lateral feed mechanism on said opposite wall comprising a plurality of straw-engaging fingers engageable and disengageable with the plurality of straws adjacent said opposite wall, an ejector at one end of said opposite wall, said container having an opening alined with said ejector through which a straw may be ejected, an operating member on said container connected to and movable in one direction to raise said ejector and to eject a straw and movable in the opposite direction to lower said ejector, and means connecting said member to said feed mechanism to disengage the mechanism from said straws and to traverse the mechanism away from said ejector upon lowering of the member, and to engage the mechanism with the straws and to traverse the mechanism toward said ejector upon raising of said member.

5. In a dispenser for soda straws comprising a container, means therewithin to press contained straws toward one wall of the container, a comb-like feed member disposed transversely adjacent said one wall, the member having an original position and being movable into engagement with straws and out of engagement therewith and being movable transversely, an operating member having elements engageable with said feed member, said elements including a depressor to tilt said feed member and a cam to move said feed member transversely upon one-directional movement of said operating member, and resilient means to untilt said member into straw engagement and to restore said feed member to its original position while moving straws therewith after disengagement of said member by said elements.

6. In a dispenser for soda straws comprising a container, means therewithin to press contained straws toward one wall of the container, a comb-like feed member disposed transversely adjacent said one wall, the member having an original position and being movable into engagement with straws and out of engagement therewith and being movable transversely, an operating member having elements engageable with said feed member, said elements including a depressor to tilt

said feed member and a cam to move said feed member transversely upon one-directional movement of said operating member, resilient means to untilt said member into straw engagement and to restore said feed member to its original position while moving straws therewith after disengagement of said member by said elements, and means responsive to operating member movement to discharge a straw, fed by said feed member, from said container.

7. In a dispenser for soda straws comprising a container, first resilient means therewithin to press contained straws toward one wall of the container, a comb-like feed member disposed transversely adjacent said one wall, the member having an original position and being movable into engagement with straws and out of engagement therewith and being movable transversely, an operating member having elements engageable with said feed member, said elements including a depressor to tilt said feed member and a cam to move said feed member transversely upon one-directional movement of said operating member, second resilient means to untilt said member into straw engagement and to restore said feed member to its original position while moving straws therewith after disengagement of said feed member by said elements, means responsive to operating member movement to discharge a straw, fed by said feed member, from said container, said first resilient means urging contained straws into engagement with said feed member.

8. In a straw dispenser, in combination, a container for a supply of straws, means therein to urge the straws toward one interior face of the container, feed means reciprocable transversely of the straws mounted on said container adjacent said face having projections engageable with said straws, an ejector for a straw at one end of said means, an operating member, and means connecting said operating member and ejector for sequential operation thereof to eject a straw and to feed another straw into position for ejection upon movement of said operating member.

9. In a straw dispenser, in combination, a container for a supply of straws having an interior face engaged by the straws, feed means mounted in said container adjacent said face movable transversely of the axes of the straws to move them toward one edge of said face, an ejector reciprocable along said edge to displace a straw axially therewith, a movable operating member, means connecting said operating member with said ejector to cause ejection of a straw upon movement of the operating member, and means connecting said operating member with said feed means to cause movement thereof upon movement of the operating member away from said ejector, and elastic means urging feeding movement of said feed means toward said ejector.
